UNITED STATES PATENT OFFICE.

HARLAN LEVEY, OF NEW YORK, N. Y.

LUMINOUS INDICATING BUTTON FOR KEYS.

Application filed February 4, 1922. Serial No. 534,147.

To all whom it may concern:

Be it known that I, HARLAN LEVEY, a citizen of the United States, and a resident of the city of New York, borough of Manhattan, in the county and State of New York, have invented a new and Improved Luminous Indicating Button for Keys, of which the following is a full, clear, and exact description.

10 This invention relates to a luminous indicating device, and has particular reference to a luminous indicating button to be attached to articles such as keys.

15 An object of the invention is to provide a simple, economically manufactured button which can be readily applied to various articles, such as keys.

20 Another object resides in the provision of means whereby the attachment to and detachment from the key or article of the button is made extremely simple so that the buttons can be readily replaced when desired.

25 A further object resides in the provision of a particular combination of articles and button which will render the operation of the article, such as a key, extremely simple in the darkness.

30 A still further object resides in the particular construction and arrangement of parts which are hereinafter described and claimed and shown in the accompanying drawings.

35 The invention is illustrated in the drawings, of which—

Figure 1 is a side view of a key with a button attached.

Fig. 2 is a sectional view taken on the line 2—2 of Fig. 1.

0 The form of the invention shown in the drawings is a preferred form, although it is understood that modifications in the construction and arrangement of the parts and in the character of the materials used may be adopted without departing from the spirit of the invention.

A preferred application of the invention, as shown in the drawings, comprises an article, such as a key, 1. This is provided, preferably, with an aperture 2 having a shoulder 3 facing one side of the key or article. The aperture has a flared surface 4 on the side of the key toward which the shoulder 3 faces.

In this aperture there is preferably disposed a button containing luminous mate-

rial 5. This button is formed of two plates or sheets 6 and 7 of material such as celluloid, which is translucent if not transparent, although it is preferably such material as will readily pass the light of the material contained within the button. These plates or sheets 6 and 7 are shaped in accordance with the configuration of the aperture or pocket 2 in which the button is disposed and are shown as circular in shape, the plate 6 being at its outer edges, as at 8, bent or crimped over the peripheral edge of the sheet or plate 7 so that a tight, firm container is formed between the plates or sheets within which the luminous material is efficiently held.

The button is placed in the aperture or pocket with the edges of the button bearing against the shoulder. Any suitable means may be adopted for holding the button within the pocket or aperture. One means for holding the button in the pocket is shown as lips 9 and 10 struck up out of the metal of the key adjacent the button and projecting over the edges of the button at two or more points to hold the button in place.

It will be understood, of course, that this aperture shown is merely one form of pocket or recess in which the button may be disposed. It is not absolutely necessary that the button be visible from both sides of the key, the idea being that on the key is disposed a luminous button which is, of course, preferably disposed as indicated. By reason of the luminous material, the manipulation of the key is made much simpler in the darkness than would be the case without the use of this material. Fresh buttons can be very readily placed on the key when desired, since the invention is not confined to the particular fastening means shown, any other suitable fastening means being adaptable for the purpose of permitting the button to be removed readily and replaced.

100 What I claim is:

In combination, a key having an opening therethrough and a shoulder in said opening, a pair of spaced sheets of transparent material, luminous material contained within said sheets, the edges of said sheets engaging each other and disposed on said shoulder, and lips struck up from the metal of the key and projecting over the edges of the sheets on the opposite sides thereof from the shoulder to hold the button in place.

HARLAN LEVEY.
